(57) **CLAIM**

The ornamental design for the brim mounted face shield, as shown and described.

DESCRIPTION

FIG. 1 is a top perspective view of the brim mounted face shield;

FIG. 2 is a bottom perspective view of the brim mounted face shield of FIG. 1;

FIG. 3 is a front view of the brim mounted face shield of FIG. 1;

FIG. 4 is a back view of the brim mounted face shield of FIG. 1;

FIG. 5 is a right side view of the brim mounted face shield of FIG. 1;

FIG. 6 is a left side view of the brim mounted face shield of FIG. 1;

FIG. 7 is a top view of the brim mounted face shield of FIG. 1;

FIG. 8 is a bottom view of the brim mounted face shield of FIG. 1; and,

FIG. 9 is a front view of the brim mounted face shield of FIG. 1 in a flat, unfolded configuration.

Broken lines in the drawings illustrate unclaimed portions of the design and form no part of the claimed design.

1 Claim, 7 Drawing Sheets
